UNITED STATES PATENT OFFICE.

ALAN ERNEST LEOFRIK CHORLTON, OF MANCHESTER, ENGLAND.

FLUID-PRESSURE ENGINE.

1,078,661.

Specification of Letters Patent. Patented Nov. 18, 1913.

Application filed June 25, 1912. Serial No. 705,697.

To all whom it may concern:

Be it known that I, ALAN ERNEST LEOFRIK CHORLTON, a subject of the King of Great Britain, residing at Salford Iron Works, 5 Manchester, in the county of Lancaster, England, have invented certain new and useful Improvements in Fluid-Pressure Engines, of which the following is a specification.

This invention relates to fluid pressure engines (including internal combustion engines) of the valveless type in which two double acting pistons connected to the same crank shaft work in cylinders placed side by side and communicating with each other by connecting chambers at each end. In an engine of this type one piston serves as an admission valve for the charge and the other as an exhaust valve.

According to this invention the double acting piston serving for admission of the motive fluid is given a lead with regard to the other piston by setting the crank pin to which it is connected at an angle to the crank pin of the exhaust piston. The lead of the admission piston may be adjusted by varying the setting of the cranks or by other convenient means so as to obtain the best results under varying conditions. In the case of valveless steam engines the admission piston has a backward lead over the exhaust piston and is formed with a steam channel affording communication at the end of each stroke between a centrally placed steam inlet and a 25 by-pass in the cylinder admitting steam to the working space of both cylinders. As applied to double acting internal combustion engines of the two stroke kind the exhaust piston is set a little in advance of the admission piston, so that the exhaust port is opened shortly before the admission port and the pressure in the cylinders and the connecting chamber at either end is released before the scavenging air enters and drives 30 out the remaining products of combustion.

As the inlet port remains open after the exhaust is closed a larger charge can be introduced than would be the case without such lag in the closing of the inlet port, full advantage being taken of the pressure in the inlet pipe. The difference in phase between the cranks may be such that the inlet port opens and closes after the exhaust closes.

In order that the said invention may be 35 clearly understood and readily carried into effect, the same will be described more fully

with reference to the accompanying drawings in which:

Figure 1 is a vertical section of a steam engine embodying my invention. Figs. 2 60 and 3 are respectively a typical indicator diagram (for the exhaust cylinder) and valve diagram of the steam engine, and Fig. 4 is a vertical section of an internal combustion engine showing the relative positions of 65 the pistons at about the end of a stroke.

A, A' are the inlet and exhaust cylinders having contracted connecting passages a of Venturi type.

B, B' are the double acting inlet and exhaust pistons with piston rods b passing through glands a' in the lower ends of the cylinders. The inlet and exhaust ports a^2 are placed centrally and extend around the circumference of each cylinder establishing 70 communication during the required intervals between the cylinders and the annular inlet and exhaust chambers C, which are secured between cylinder flanges a^3 .

The cylinders illustrated are of special 80 construction, forming the subject of another application of even date, and this construction, in which the cylinders consist of two single walled U-shaped tubes one inverted over the other and carrying the annular inlet and exhaust boxes between their uniting 85 flanges a^3 , is no part of the present invention.

Referring to Fig. 1 the inlet piston B is of 90 different form to the exhaust piston B' and is substantially longer. The central portion or body of the piston is reduced to form end flanges and a central annular chamber or channel b' which is open to the inlet chamber C through the ports a^2 toward the end 95 of a stroke and establishes communication between these ports and the lower end of the by-pass a^4 leading to the back of the piston. The drawing shows the position of the piston when steam is being admitted to 100 the upper end of the cylinders, a by-pass a^4 being placed at each end of the inlet cylinder. The by-pass is shown as a passage leading through the cylinder walls but may of course be of any other suitable form such 105 as a channel or channels in the inner face of the cylinder.

The cranks to which the pistons are connected are, as shown diagrammatically in Fig. 3, set at an angle to each other, d indicating the position of the exhaust crank and D the position of the inlet crank near the 110

dead center, the former crank being set in advance of the latter so that the inlet piston lags behind the exhaust piston and the relative position of the pistons at about the end of a stroke is approximately as shown in Fig. 1.

The manner in which the engine operates is as follows:—The channel b' of the inlet piston B is open continuously to the inlet ports a^2 belonging to the inlet cylinder A, but the channel communicates with one of the by-passes a^1 only when the corresponding end flange of the piston uncovers the end of the by-pass as shown for the upper by-pass in Fig. 1. The point in the upward movement of the piston when this occurs is shown at D in the valve diagram Fig. 2 (D giving the angular position of the crank), and the by-pass remains open until the piston reaches the top of its stroke and returns to the same position, when the steam to the top working chambers of the two cylinders A and A' is cut off. The corresponding crank position is indicated at D' in the diagram. As the exhaust piston B' is given a forward lead over the inlet piston B the positions of the exhaust crank corresponding to the points D and D' on the diagram are indicated by the points d and d', the angle of lead (which may of course be variable to suit varying conditions of working) being given by the angular distance between D and d or between D' and d'. This angle it will be observed is a small one, and the arrangement is thus clearly distinguished from engines having two pistons in parallel cylinders, the cranks of which pistons are set at right angles to each other, while the pistons themselves act as inlet and exhaust valves one for the other. Such an angular setting does not give any lead, as the admission of steam to both cylinders is not simultaneous but is out of phase to the same extent as the pistons themselves. Considering the exhaust, this is opened when the upper edge of the exhaust piston B' uncovers the ports a^2 in the cylinder A' and the position of the crank of this piston at the opening of the exhaust is indicated by the point d^2 of Fig. 2, the exhaust remaining open until the piston B' completes its downward stroke and returns to the same position in the cylinder, corresponding to the point d^3 of the diagram.

55 The pressure diagram of Fig. 2 further illustrates the operation of the engine, and from this diagram it will be understood that suction occurs from the point d^3 to the point d. From point d to d' the motor fluid is supplied at constant pressure; from d' to d^2 the motor fluid expands during working, and from d^2 to d^3 exhaust takes place. The engine above described may also be

driven by working fluid other than steam, if the working fluid is supplied to the cylinders under pressure, as, for example, in the case of hot air engines.

In the internal combustion engine shown in Fig. 4 the inlet and exhaust pistons B and B' are similar to each other and the exhaust piston B' is set a little in advance of the inlet piston B, so that the ports a^2 of the exhaust are uncovered before the inlet ports and the incoming charge meets with no appreciable back pressure until the exhaust closes, which occurs shortly before the closing of the inlet permitting a full charge under the pressure of the delivery pump to be introduced.

The annular inlet chamber C' may be provided with the partition c to admit separate air and fuel charges, the air entering first as a scavenging charge, to be followed by the combustible mixture. As in the case of the steam engine first described the cycle of operations is the same for both ends of the cylinders.

What I claim and desire to secure by Letters Patent of the United States is:—

1. In a valveless fluid pressure engine, two cylinders placed side by side, open communicating passages between both ends of the cylinders, inlet ports midway of one cylinder, exhaust ports midway of the second cylinder and a double acting piston in each cylinder, one of the said pistons being given a lead with respect to the other.

2. In a valveless steam engine, communicating admission and exhaust cylinders placed side by side, central inlet and exhaust ports for the said cylinders, steam by-pass channels at each end of the admission cylinder, a double acting exhaust piston and a double acting admission piston having a steam channel adapted to afford communication between the inlet port and the said by-pass at the end of a stroke.

3. In a valveless steam engine, communicating admission and exhaust cylinders placed side by side, central inlet and exhaust ports for the said cylinders, steam by-pass channels at each end of the admission cylinder, a double acting exhaust piston and a double acting admission piston the body of which is reduced to form an annular surrounding steam space in communication with the inlet port and adapted to open the inlet to the said by-pass at the end of a stroke.

In testimony whereof I affix my signature in presence of two witnesses.

ALAN ERNEST LEOFRIE CHORLTON.
